UNITED STATES PATENT OFFICE.

WILLIAM H. MILLER, OF TORONTO, KANSAS.

COLLAR PAD.

Application filed June 20, 1927. Serial No. 200,157.

The present invention relates to improvements in pads for horse collars and the primary object of the invention is to provide a pad of this character embodying a cap of novel construction for maintaining the pad proper from losing its proper shape after continued use.

A further object of the invention is to provide an improved horse collar pad embodying features whereby the pad is held against movement from its proper location beneath the collar, and one of such formation as to distribute the load or weight of the collar evenly over a large portion of the horse's neck.

A still further object of the invention is to provide a pad of this character embodying a cap so reinforced as to permit of the same being formed from relatively light sheet metal without liability of the cap becoming distorted during use.

Other objects and advantages of the invention will be apparent during the course of the following detailed description, taken in connection with the accompanying drawing forming a part of this specification and in which drawing.

Figure 1 is a view showing the improved pad in use.

Figure 2 is an enlarged top plan view of the pad.

Figure 3 is a transverse section on line 3-3 of Figure 2.

Figure 4 is a central longitudinal section through the improved pad.

Figure 5 is a perspective view of one of the combined reinforcing and position retaining flanges of the cap for the pad.

Referring to the drawing in detail, and wherein similar reference characters designate corresponding parts throughout the several views, the improved collar pad has been shown as comprising a cap A, a lining or pad proper B, and fastening means C for attachment of the pad to the upper portion of a collar D.

Referring first to the specific construction of the cap A, the same is formed from a suitable gauge sheet of metal shaped to provide an elongated transversely arcuated plate portion 10. The front and rear terminal portions of the arcuated plate portion 10 are bent inwardly into contacting engagement with the upper convex side of the plate for providing terminal reinforcing beads 11 and also presenting rounded edges at the front

and rear ends of the plate. Extending in parallel spaced apart relation transversely of the upper convex side of the plate portion 10, and spaced inwardly from the terminal reinforcing beads 11, is a pair of L-shaped reinforcing flanges 12 each embodying an upstanding portion 13 and a right angularly offset foot portion 14 conforming to the curvature of the convex side of the plate portion 10. These flanges 12 are of a length equal to the width of the plate portion 10 as is clearly illustrated in Figures 2 and 3, and are preferably secured to the plate portion by welding the foot portions 14 to the convex side of the plate portion with the foot portions of the flanges extending toward the terminal portions of the plate. These spaced, transversely extending reinforcing flanges 12 form a channel like saddle at the intermediate portion of the plate 10, and which saddle is intended to receive the upper portion of the collar D between the flanges 12. Thus it will be seen that the flanges 12 aside from materially reinforcing the transversely arcuated plate portion 10, also form a saddle in which the collar rests at a point intermediate the ends of the cap.

The lining or pad proper B, and which may either be formed of leather, canvas, or any other suitable material, is of substantially rectangular shape in formation and of a size so that when the lining is secured in position at the concaved side of the cap A, the marginal portions of the lining will extend well past the marginal edges of the cap as illustrated in Figure 2. In the example shown the lining B is doubled upon itself at its side and end edges. The terminally doubled portions 15 of the lining provide means whereby the terminal portions of the lining may be secured to the terminal portions of the cap A as by means of suitable rivets 16 which extend through the doubled material 15 and through the beads 11. Thus the beads 11 aside from serving to reinforce the terminal portions of the plate 10, also provide a double thickness of metal for preventing the rivets 16 from pulling loose from the cap.

The fastening means C for attachment of the pad to the collar C preferably consists of a pair of straps 20 provided at one terminal with a suitable buckle 21. These straps 20 are secured intermediate their ends to the side portions of the lining B which project past the side edges of the cap plate portion

10 as by means of suitable rivets 22 which a saddle intermediate the ends of the cap extend through the straps and the doubled 45 side edges of the lining. These straps 20 are secured longitudinally of the cap A at 5 points aligning transversely of the pad with the saddle or seat space 25 formed between the flanges 12. Thus it will be seen that when the upper portion of the collar D is placed between the flanges 12 that the straps 10 20 may be readily passed about the collar to each side of the cap A for fastening of the pad in position beneath the upper portion 15 of the collar. This attaching of the straps 20 to the flexible portion of the pad will allow for the side edges of the lining to be drawn into contact with the inner surface of the collar and be prevented from tearing at the edges. When the upper portion 20 of the collar is seated between the flanges 12 it will be seen that the flanges 25 form a saddle and engage the front and rear portions of the collar in a manner whereby the pad is prevented from slipping back and forth on the horse's neck and is held in proper relation to the collar at all times.

From the foregoing description it will be apparent that an improved pad for horse collars has been provided embodying a novelly constructed cap whereby the weight of the collar is distributed evenly over a large bearing surface, and one embodying novel features of construction whereby the pad is effectively held from slipping back and forth on the horse's neck. It will also be apparent that an improved cap has been provided embodying reinforcing means so arranged as to permit of the cap being formed of relatively light sheet metal without becoming distorted in use, and certain of which reinforcing means serves to form

a saddle intermediate the ends of the cap for receiving the upper portion of the collar.

Changes in detail may be made to the specific form of the invention herein shown and described, without departing from the spirit of the invention or the scope of the following claims.

I claim:

1. A collar pad comprising a cap embodying an elongated transversely arcuated sheet metal plate portion having its end edges doubled to form terminal reinforcing beads and flanges secured in spaced relation transversely of the plate portion at the upper convex face thereof and extending throughout the width of the plate portion, a lining arranged at the under concaved side of the plate portion with its marginal edges projecting past each marginal edge of the plate portion, means for securing the end portions of the lining to the terminal reinforcing beads of the plate portion, and a fastening strap secured to the outer side of the lining at each side edge thereof between said transversely extending flanges.

2. In a pad for horse collars, a cap embodying an elongated transversely arcuated sheet metal plate portion having its front and rear end edges bent inwardly in surface contact with the upper convex face of the plate for forming a terminal reinforcing bead at each end of the plate, and a pair of L-shaped flanges secured in parallel spaced relation transversely of the convex side of the plate portion and extending throughout the width thereof, said flanges conforming to the transverse curvature of the plate portion and forming a saddle at the intermediate portion of the plate portion.

WILLIAM H. MILLER.
